UNITED STATES PATENT OFFICE.

EMIL R. LOCHMAN, OF BOSTON, MASSACHUSETTS.

TRACING DEVICE FOR COPYING OR DUPLICATING MACHINES.

1,084,155.

Specification of Letters Patent. Patented Jan. 13, 1914.

Application filed May 21, 1910. Serial No. 562,649.

To all whom it may concern:

Be it known that I, EMIL R. LOCHMAN, a citizen of the United States, residing at Boston, in the county of Suffolk and State of Massachusetts, have invented new and useful Improvements in Tracing Devices for Copying or Duplicating Machines, of which the following is a specification.

This invention relates to improvements in machines for duplicating or reproducing objects and designs by the use of a master-pattern by which a suitable work-performing tool is controlled in its action upon the work by the movements of a tracing tool moved over the surface of the master-pattern by the operator.

While the device which forms the subject matter of my present invention may be employed in connection with duplicating machines of various types and while its field of usefulness may extend even to other classes of machines, I have for the purpose of illustration shown in the drawings my present invention in connection with a stone and metal cutting and carving machine forming the subject matter of an application for Letters Patent of the United States filed by me October 7, 1908, Serial No. 397,702. The master pattern used in connection with machines of this class is often made of fragile material such, for example, as plaster and the material being cut by the work-performing tool is often very hard such, for example, as stone, as a consequence of which great care must be exercised by the operator to prevent the tracing tool from injuring the delicate master-pattern over which it is moved by the hand of the operator. It is necessary for the operator to give considerable attention to the action of the work-performing tool and yet at the same time it is necessary for him to carefully watch the tracing tool, otherwise, when he is forcing the work-performing tool into the work, the tracing tool might be carried against some part of the master-pattern with sufficient force to injure the same, this being especially true where there are very delicate raised surfaces on the pattern and injury to such parts would entail considerable loss.

It is the object of my present invention to provide means to prevent such injury to the master-pattern by the tracing tool, either by giving the operator a visible or audible warning signal when the tracing tool touches any part of the master-pattern, or

by preventing further movement of the tracing tool when it has come into contact with the pattern.

To this end, my invention consists broadly in the combination with a tracing tool and its holder of normally inactive means rendered active by the movement of the tracing tool relative to the holder due to contact of the tracing tool with the master-pattern, such normally inactive means consisting either of a suitable signal device or consisting of means to arrest the movement of the tracing tool when it contacts with the master-pattern and thus positively preventing injury to the pattern.

My invention further consists in a novel circuit making and breaking device particularly adapted for use in connection with tracing tools of duplicating machines and adapted to complete an electric circuit when the tracing tool contacts with the master-pattern at any point.

My invention still further consists in the combination of a circuit making and breaking device operating as just described with normally inactive means rendered active by the completion of the circuit by said device.

My invention finally consists in the novel features of construction and in the combination and arrangement of parts set forth in the following specification and particularly pointed out in the claims.

Referring to the drawings: Figure 1 is a plan of a portion of a duplicating machine to which the devices embodying my present invention are applied. Fig. 2 is a front elevation of the machine with its work-supporting platen shown in section and with the master-pattern and two pieces of work being reproduced therefrom also shown in section. Fig. 3 is a sectional view of the machine taken on line 3—3 of Fig. 2, looking toward the left. Fig. 4 is an enlarged vertical sectional view of the tracing tool, its holder, the circuit making and breaking device operated by the tracing tool, and a portion of the carrier upon which the holder is mounted, the parts being shown in their normal position. Fig. 5 is a sectional view similar to Fig. 4 with the holder partly broken away, the parts being shown in the position which they occupy when the point of the tracing tool is carried laterally toward the left by contact with the master-pattern. Fig. 6 is a detail plan section taken on the irregular line 6—6 of Fig. 4. Fig. 7 is a sectional view

taken on line 7—7 of Fig. 6. Fig. 8 is a diagram of the wiring of the electrical devices of the machine in which electric lamps are employed as the normally inactive means 5 are rendered operative by the completion of the circuit. Fig. 9 is a diagram of the wiring of the electric devices of the machine where the normally inactive means rendered active by the completion of the circuit consists of an audible signal such as an electric bell. Fig. 10 is a diagrammatic view illustrating a modified view of my invention in which the normally inactive means rendered active by the completion of the circuit 10 consists of electrical devices to arrest movement of the tool carrier when the tracing tool has come into contact with the master-pattern. Fig. 11 is a diagrammatic view of another modified form of 15 my invention in which the normally inactive means rendered active by the completion of the circuit making and breaking device consists of combined electric and fluid operated instrumentalities to arrest the movement of 20 the tool carrier when the tracing tool has come into contact with the master-pattern. Fig. 12 is a vertical sectional view of a modified form of the tracing tool or stylus and the circuit breaking device which it 25 actuates.

In the drawings, 15 is a tool carrier upon which two suitable working tools 16, 16 are mounted, said carrier being journaled in bearings 17, 17 having pivotal connection, 30 respectively, with levers 18, 18 fulcrumed upon a rock shaft 19 and said levers being pivotally connected to each other at their rear ends by a link 20 constituting a counter weight. The rock shaft 19 is mounted to 35 rock upon a pair of slides 21, 21 constituting a carriage mounted to slide upon suitable ways 22, 22 and caused to travel in parallelism by drums 23, 23 connected to their respective slides by suitable means such, for 40 example, as a pair of flexible cords 24, 24 for each drum, these drums being secured to a shaft 25 journaled in the side members 26, 26 of the frame of the machine.

Mounted upon the tool carrier 15 in any 45 suitable manner is a tracing tool holder 27 on which is journaled a collar 28 having pivotal and sliding connection with an operating lever 29 fulcrumed at its rear end on the rock shaft 19 and provided at its forward end 50 with a handle 30 for manual operation. By means of this handle, the operator is enabled to move the tool carrier 15 forward and back, up and down and right and left, since the mechanism hereinbefore described 55 constitutes a means permitting universal movement of the tool carrier, this mechanism forming a part of the subject matter of the aforesaid application for Letters Patent of the United States.

60 A suitable platen 31 supports a suitable

preferably, non-conducting master-pattern 32 of which pattern the working tools 16 are adapted to make reproductions 33 by cutting or otherwise operating upon the same, the movement of these working tools being 65 under the manual control of the operator by means of the handle 30, there being provided a tracing tool or stylus 34 which coacts with the master-pattern 32 in such a manner as to act as a guide for the operator and thus 70 enable him to make exact reproductions of the pattern.

75 I will now proceed to describe the novel devices which form the subject matter of my present invention.

80 The tracing tool 34 which is formed of any suitable material according to the nature of the master-pattern 32 is provided with a screw-threaded shank 35 by which it is screwed into a sleeve 36 so that it is possible 85 to remove the tracing tool from time to time and replace it by others of different sizes and shapes suitable for the particular master-pattern or parts thereof. The sleeve 36 is provided with an axial bore 37 in which 90 is located a plunger 38 telescopically arranged therein, said plunger, in practice, being fitted to the bore of said sleeve with a clearance of only a fraction of a thousandth of an inch sufficient to permit the introduction 95 of the thinnest oils. If desired, a pin 39 may be inserted in the plunger 38 and arranged with its outer end to slide vertically in a slot 40 provided in the sleeve 36 to prevent turning movement of said plunger in 100 said sleeve.

105 Surrounding the plunger 38 is a spring 41 bearing at its lower end against the upper end of the sleeve 36 and bearing at its upper end against a shoulder 42 provided on said plunger, said spring tending to extend the two telescopically arranged parts 36 and 38. The plunger 38 is provided in its upper end with a concavity 43 preferably of conical form, this concavity constituting a seat for 110 a ball 44. Located above this ball is a plug 45 also provided with a similar concavity 46 constituting an upper seat for the ball 44, said plug having screw-threaded engagement with a sleeve 47 in which it may be 115 adjusted vertically, there being provided a screw 48 having screw-threaded engagement with a yielding portion 49 of said plug formed by a slot 50 by means of which said plug may be securely locked in its adjusted 120 position in said sleeve within which it is mounted.

125 The sleeve 47 is surrounded by a sleeve 51 of insulating material, the latter sleeve being mounted in the holder 27 which is slotted 52 and provided with a clamping nut 53 having a tapered portion 54 by which said holder is caused to clamp the sleeve 51 which in turn causes the sleeve 47 to be clamped. In this way, the parts are securely 130

held in the holder 27, but insulated therefrom. The sleeve 47 where it extends downwardly beyond the insulating sleeve 51 has screw-threaded engagement with a ring 55 provided with a spherical socket 56 in which is fitted a corresponding spherical surface 57 formed on the sleeve 36, these parts constituting a ball and socket or universal joint permitting lateral swinging movement of the tracing tool 34, the sleeve 36 and the plunger 38 which is telescopically arranged with relation to said sleeve.

The bore 37 of the sleeve 36 constitutes a chamber wherein are located two terminals 58 and 59 normally separated from each other by a slight space. These terminals are, in practice, formed of a suitable material such, for example, as platinum. The upper terminal 59 is yieldingly mounted in any suitable manner, as by being inserted in a spring-pressed plunger 60 mounted to slide within an axial bore 61 provided in the plunger 38, the vertical travel of the plunger 60 being limited by a pin 62 passing therethrough into a slot 63 provided in the plunger 38.

The terminal 58 is mounted in a holder 64 which is mounted in an insulating bushing 65 having screw-threaded engagement with the sleeve 36 and projecting outwardly through a vertical slot 66 provided in the ring 55. The holder 64 is screwed into a binding post 67 surrounded by an insulating sleeve 68 and provided with a sleeve nut 69. The binding post 67 is provided with a groove 70 in which extends a line wire 71, said wire extending between one end of the sleeve nut 69 and one end of the insulating sleeve 68 and being clamped therebetween by the co-operative action of said sleeve nut with said binding post. Preferably, the sleeve nut is provided with an outwardly flared entrance 72 for the insulated portion of the line wire 71 so as to prevent said wire from being broken off owing to the continual flexing of said wire.

The collar 55 is provided with a notch 73 allowing a free play of the sleeve 68 with respect thereto during vertical movements or lateral swinging movements of the sleeve 36. It will be noted that the sleeve 36 is provided with a shoulder 74 separated from the lower end of the sleeve 47 by a slight space, this space being sufficient to allow the sleeve 36 to swing laterally owing to its ball and socket connection with the collar 55 and to slide vertically with relation to the sleeve 47, such vertical sliding movement resulting in the terminal 58 being carried upwardly into contact with the terminal 59 and said swinging movement causing the ball 44 to act, as shown in Fig. 5, to force the plunger 38 downwardly to carry the terminal 59 into contact with the terminal 58. Thus it will be evident that whenever the tracing tool 34 comes into contact with the master-pattern by movement in any direction, the two terminals 58 and 59 will be carried into contact with each other.

The holder 64 for the terminal 58 is screwed into place in the binding post 67 through a screw-threaded hole 75 provided in the sleeve 36 into which hole is screwed a screw 76, the head of which plays in a vertical slot 77 provided in the ring 55.

When it is desired to render the circuit making and breaking device inoperative, this is accomplished by rotating the ring 55 in a proper direction to carry the shoulder 74 into contact with the lower extremity of the sleeve 47, thereby rendering the tracing tool 34 perfectly rigid. A screw 78 having screw-threaded engagement with the ring 55 is provided with a reduced cylindrical projection 79 located in a segmental slot 80 provided in the screw-threaded portion of the sleeve 47, this screw 78 serving to normally lock said sleeve against rotation. This slot is of such extent that when the ring 55 has been screwed up to carry the shoulder 74 into contact with the lower extremity of the sleeve 47 some space still exists beyond the projection 79 in the direction in which said screw is revolving about the axis of said sleeve and the other limit of said slot 95 is so placed that when said ring is rotated in the opposite direction to carry the shoulder 74 out of contact with the lower extremity of the sleeve 47, the proper amount of separation of the terminals 58 and 59 to 100 break the circuit is positively determined.

The spring-pressed plunger 60 in which the terminal 59 is mounted prevents injury to said terminal which might occur if it were subjected to undue pressure. The terminal 59 is electrically connected with the ring 55 through the contact of the metallic parts connecting said terminal and said ring. The ring 55 is provided with a binding post 81 having a sleeve 82 and sleeve nut 83, 110 said binding post being provided with a slot 84 in which is located a line wire 85 extending between said sleeve and said sleeve nut, these parts being all identical with the parts of the binding post 67 hereinbefore 115 described. The line wires 85 form a part of an electric circuit having therein normally inactive means rendered active upon completion of the circuit by the contact of the terminals 58 and 59. In Fig. 8, said 120 means is shown as a visible signal consisting of one or more electric lamps 86 which may be suitably placed upon the machine preferably one adjacent to each of the working tools 16. In Fig. 9, the normally inactive means rendered active by the completion of the circuit consists of an electric bell 87 which gives an audible signal to the workman. In Fig. 10, the normally inactive means rendered 130

active by the completion of the circuit consists of a pair of solenoids 88 in the circuit, said solenoids having armatures 89 operatively connected to the tool carrier 15 in such a manner that when the tracing tool comes into contact with the master-pattern, the completion of the circuit results in the solenoids being energized and thus arresting the tracing tool in its travel and consequently positively preventing the tracing tool from injuring the master-pattern. In Fig. 11, I have shown still another modification of my invention in which the normally inactive means rendered active by the completion of the circuit consists of a solenoid 90 which, when energized, is adapted to move a valve 91 into position to allow some suitable fluid under pressure to flow from a suitable source, not shown, through a pipe 92 and a pipe 93 to the under side of a piston 94 arranged to reciprocate in a cylinder 95, said piston being operatively connected to the tool carrier 15. A spring 96 is provided to return the valve 91 to its initial position after being carried therefrom under the influence of the solenoid 90 and a spring 97 is provided to assist gravity in returning the piston 94 to its initial position. In this form of my invention also when the circuit is completed, the tracing tool is arrested in its movement by the fluid pressure acting on the piston 94 and in this way the tracing tool is positively prevented injuring the master-pattern.

It will be understood that my invention comprehends any means whatever normally inactive and rendered active by movement of the tracing tool in its holder, whether said means consists of signal devices or devices for actually performing work such, for example, as controlling the movement of the tool bar and the tracing tool.

Referring now to Fig. 12 wherein is shown a modified form of circuit making and breaking device for use in connection with the stylus, 98 is a tracing tool or stylus which is formed of any suitable material, preferably a non-conducting material, screwed onto a screw-threaded shank 99 on a member 100 which constitutes one of the terminals of the device, said member having electrically connected thereto a line wire 101 passing into an elbow 102 of non-conducting material screwed into said member, the end of said wire being electrically connected to said member in any suitable manner. This member is provided with a contact point 103 adapted to make and break contact with a contact point 104 provided thereabove in a sleeve 105 surrounding said member. The member 100 is mounted within the sleeve 105 for vertical as well as lateral movement, said member being provided with a spherical surface 106 seated in a spherical seat 107 formed of insulating material, said seat be-

ing supported in a socket 108 consisting of a ring having screw-threaded engagement with the sleeve 105. A helical compression spring 109 bears at its lower end against a shoulder 110 formed on the member 100 and bears at its upper end against a sleeve 111 of insulating material surrounding the upper extremity of said member and constituting a guide therefor. Thus it will be seen that the member 100 which constitutes one of the terminals of the circuit making and breaking device is normally insulated from the sleeve 105 and ring 108 and is capable of a universal movement therein. A second line wire 112 is connected to a suitable binding post 113 secured to the ring 108. The sleeve 105 is surrounded by a sleeve 114 of insulating material, the latter sleeve in turn being mounted within a holder 115 in any suitable manner.

The operation of the device is as follows: If the device be moved downwardly, the stylus 98 by contact with the master-pattern will yield upwardly carrying the contact point 103 into contact with the contact point 104, thus making electrical connection between the member 100 and the sleeve 105 and completing the circuit between the line wires 101 and 112. If, on the other hand, the device be moved laterally, the stylus 98 by contact with the pattern will act to move the member 100 laterally, this resulting in said member contacting with the inner periphery of the lower portion of the sleeve 108 and also at the same time owing to the co-operative action of the spherical surface 106 in the seat 107, said member will be forced upwardly, thus carrying the contact point 103 into contact with the contact point 104 so that at either or both of the two points described, the circuit is completed. The circuit may be completed at still another point, if desired, by providing the member 100 with a shoulder 116 adapted to contact with the lower extremity of the sleeve 105.

It will be observed that the member 100 is capable of universal movement so that whenever the stylus 98 contacts with the master-pattern it causes the circuit making and breaking device to complete the circuit.

It will be understood that my invention comprehends broadly any circuit making and breaking means actuated by movement of the stylus or tracing tool and I do not limit myself to either of the two devices shown and described except where such limitations are pointed out in certain of the claims.

Having thus described my invention, what I claim and desire by Letters Patent to secure is:

1. A machine of the class described having, in combination, a carrier, means on which said carrier is mounted for universal movement, a working tool carried by said

carrier, a tracing tool mounted on said carrier for universal movement with respect to said carrier, and means adapted to be actuated by movement of said tracing tool relatively to said carrier, to move said carrier away from the work.

2. A circuit making and breaking device having, in combination, two telescopically arranged members carrying normally separated terminals, a holder in which said members are mounted for lateral movement relative to said holder, means connecting said holder to one of said members whereby lateral movement of said members relative to said holder imparts a relative telescopic movement to said members to carry said terminals into contact with each other, and yieldable means acting upon said members to normally hold said terminals in separated relation.

3. A circuit making and breaking device having, in combination, two telescopically arranged members one of which is provided with a chamber, two normally separated terminals located in said chamber, a holder in which said members are mounted for lateral movement relative to said holder, means connecting said holder to one of said members whereby lateral movement of said members relative to said holder imparts a relative telescopic movement to said members to carry said terminals into contact with each other, and yieldable means acting upon said members to normally hold said terminals in separated relation.

4. A circuit making and breaking device having, in combination, two telescopically arranged members one of which is provided with a chamber, two normally separated terminals located in said chamber and carried by said members, respectively, means by which one of said terminals is insulated from the said member by which it is carried, a holder in which said members are mounted for lateral movement relative to said holder, means connecting said holder to one of said members whereby lateral movement of said members relative to said holder imparts a relative telescopic movement to said members to carry said terminals into contact with each other, and yieldable means tending to extend said telescopic members and acting thereby to hold said terminals in separated relation.

5. A circuit making and breaking device having, in combination, two telescopically arranged members carrying normally separated terminals, one of said members being provided with a concavity forming a seat, a holder in which said members are mounted for lateral movement relative to said holder, said holder having therein a concavity forming a seat opposed to the first-mentioned seat, a convex element interposed between said seats, and a spring tending to relatively ex-

tend said members and acting thereby to urge said convex element into central position in said seats whereby said terminals are normally held in separated relation.

6. A circuit making and breaking device having, in combination, two telescopically arranged members carrying normally separated terminals one of said members being provided with a concavity forming a seat, a holder in which said members are mounted, said holder having therein a concavity forming a seat opposed to the first-mentioned seat, a convex element interposed between said seats, a ball and socket joint connecting said members to said holder permitting swinging movement of said members relative to said holder, and a spring tending to relatively extend said members and acting thereby to urge said convex element into central position in said seats whereby said terminals are normally held in separated relation.

7. A circuit making and breaking device having, in combination, two normally separated terminals, two members connected to each other for relative movement in two directions one transverse to the other, to carry said terminals into contact with each other by either of said movements, one of said terminals being yieldingly mounted in one of said members, the other of said terminals being fixed in the other of said members, and yieldable means acting upon said members to normally hold said terminals in separated relation.

8. A circuit making and breaking device having, in combination, two telescopically arranged members one of which is provided with a chamber in which are located two normally separated terminals carried by said members, respectively, a sleeve in which said members are located, a ring mounted on said sleeve and provided with a spherical socket, one of said members being provided with a spherical surface fitting said socket and the other of said members being provided at one end with a concavity forming a seat, said sleeve having therein a concavity forming a seat opposed to the first-mentioned seat, a ball interposed between said seats, and a spring tending to relatively extend said members and acting thereby to urge said ball into a central position in said seats whereby said members are held in coaxial alignment with said sleeve and said terminals are normally held in separated relation.

9. A circuit making and breaking device having, in combination, two telescopically arranged members one of which is provided with a chamber in which are located two normally separated terminals carried by said members, respectively, a sleeve in which said members are located, a ring having screw-threaded engagement with said sleeve and

- provided with a spherical socket, one of said members being provided with a spherical surface fitting said socket and the other of said members being provided at one end 5 with a concavity forming a seat, said sleeve having therein a concavity forming a seat opposed to the first-mentioned seat, a ball interposed between said seats, and a spring tending to relatively extend said members 10 and acting thereby to urge said ball into a central position in said seats, whereby said members are held in coaxial alinement with said sleeve and said terminals are normally held in separated relation.
- 15 10. A circuit making and breaking device having, in combination, two telescopically arranged members one of which is provided with a chamber in which are located two normally separated terminals carried by 20 said members, respectively, a sleeve in which said members are located, a ring mounted on said sleeve and provided with a spherical socket, one of said members being provided with a spherical surface fitting said socket 25 and the other of said members being provided at one end with a concavity forming a seat, said sleeve having therein a concavity forming a seat opposed to the first-mentioned seat, a ball interposed between said 30 seats, a spring tending to relatively extend said members and acting thereby to urge said ball into a central position in said seats, whereby said members are held in coaxial alinement with said sleeve and said terminals are normally held in separated relation, 35 and a mounting in which said sleeve is supported and from which said sleeve is insulated.
11. A tracing device having, in combination, a stylus, a part to which said stylus is movably connected, circuit making and breaking means actuated by movement of said stylus relative to said part, and means by which said stylus may be held in fixed 40 position with relation to said part, whereby said circuit making and breaking means is rendered inoperative.
12. A machine of the class described having, in combination, a working tool, a tracing tool, a holder in which said tracing tool 50 is mounted for universal movement, a universally movable carrier upon which said holder and said working tool are mounted whereby a movement of one of said tools may be transmitted to the other of said tools, 55 a circuit making and breaking means actuated by the movement of said tracing tool relatively to said holder.
13. A circuit making and breaking device having, in combination, two normally separated terminals, two members connected to each other for relative movement in two directions, one transverse to the other, to carry said terminals into contact with each other by either of said movements, one of said 60 members constituting a tracing tool, and yieldable means acting upon said members to normally hold said terminals in separated relation.
14. A circuit making and breaking device 65 having, in combination, two normally separated terminals, a tool, a tool holder, a ball and socket joint connecting said tool and said holder permitting relative swinging movement and relative telescopic movement 70 thereof to carry said terminals into contact with each other, and elastic means acting upon said tool to normally hold said terminals in separated relation.
15. A circuit making and breaking device 75 having, in combination, two normally separated terminals, two members connected to each other for relative movement in two directions, one transverse to the other, to carry said terminals into contact with each other 80 by a combination of said movement, one of said members constituting a tracing tool, and yieldable means acting upon said members to normally hold said terminals in separated relation.
- In testimony whereof I have hereunto set my hand in presence of two subscribing witnesses.
